TRACTION MECHANISM

Glenway Maxon, Jr., Milwaukee, Wis.

Application November 22, 1937, Serial No. 175,803

13 Claims. (Cl. 180—8)

The invention relates to traction mechanism for walking tractors.

One of the main objects of the present invention is to provide a traction mechanism having great stability and at the same time less tail clearance than those of the prior art. According to the present invention, the traction mechanism includes a hollow body or foundation unit and a foot working within the hollow of said unit and cooperating therewith to advance the unit in one direction. A hollow body has the advantage of being more stable than a solid body under working conditions in machines in which walking mechanism is usually used, and it may be increased in size without changing any other part of the mechanism. As the body determines the outside dimensions of my apparatus, less tail clearance is necessary as compared to the usual walking tractors, and as a consequence my traction mechanism may be used as a shovel or be convertible for shovel, drag-line, or ditcher equipment. As only one foot is used in conjunction with the body, the traction mechanism may be made lighter and at less expense than the usual walking type tractors. Furthermore, the arrangement has the advantage of locating the element used for travel more centrally than the working foundation so that the inertia of swinging is less than exteriorly disposed travel elements.

A further object of the invention is to provide a walking mechanism in which a vertically extensible element, working through a bell crank, can lift or partially relieve the weight of the machine on its foundation, and at the same time transmit a horizontal force sufficient to move or slide the foundation on the surface upon which it rests.

A further object of the invention is to provide a walking mechanism in which the return stroke takes place much more quickly than the working stroke.

A further object of the invention is to provide an adjustable connection between parts of the walking mechanism whereby the relationship between vertical and horizontal forces can be modified for hill climbing or even vertical jacking.

A further object of the invention is to provide a walking mechanism whose direction of movement may be reversed if desired.

A further object of the invention is to provide extensible hydraulically operated elements between the foundation and the traveling element.

The invention further consists in the several features hereinafter set forth and more particularly defined by claims at the conclusion hereof.

55 In the drawings:

Fig. 1 is a vertical sectional view through an apparatus embodying the invention, parts being broken away;

Fig. 2 is a plan view of the apparatus, oil tank being omitted;

Fig. 3 is a detailed elevation view through the hydraulic operating mechanism, parts being broken away and parts being shown in section;

Fig. 4 is a detailed view of one of the hydraulic circuits, the valve being shown in section.

Referring to the drawings, the apparatus comprises a hollow foundation or body unit 6, a foot or travel member 7 working within the hollow of said unit, and means for alternately raising and shifting these parts relative to each other to move the apparatus in one direction.

The foundation or body unit 6 preferably has a base member 8 upon which a roller-supported turntable 9 is mounted, said turntable forming the rotating base of the machine upon which a boom 10 or other equipment for excavating or other machines may be mounted.

The travel member 7 is pivotally connected at each of its opposite ends to one of the arms of bell crank levers 11. Each of these levers is operatively connected by a link 12 to the base 9. The other arm of each lever 11 has an extensible operating connection with the frame 13 of the base 9. As the member 7 is carried by the base, it will revolve with said base, and the levers 11 are so positioned as to mount said member 7 for movement toward or away from the boom or the front end of the apparatus.

The extensible operating connection between each lever 11 and the frame 13 comprises a hydraulic cylinder 14 pivotally connected at its lower end 14' to said lever 11 and a piston 15 working in said cylinder and having its rod 16 pivotally connected at its upper end to a shaft 17 carried by the frame 13. The piston 15 and its rod 16 is preferably provided with a duct 18 into which hydraulic fluid is introduced from a pipe 19 to move the cylinder 14 outwardly while hydraulic fluid introduced into the cylinder from a pipe 20 acts to move the cylinder upwardly relative to the piston. These connections are alternately established through a control valve hereinafter described.

The pipe 18 for each cylinder connects with one side of a valve housing 21 while the pipe 20 connects with the opposite side of said housing. A pressure supply pipe 22 leads from the pump 23 to the housing, and a fluid tank 24 has a pipe 24' provided with a branch pipe 25 connected with the inlet of the pump 23 and a branch pipe 26

connected with the housing 21. A plug valve 27 works in a bore 28 in the housing and has a through passage 29 connecting the pressure pipe 22 with the return 26 for no delivery, a groove 30 5 for connecting the pipe 19 either with the pipe 26 or the pipe 22 and a groove 31 for connecting the pipe 20 either with the pipe 22 or the pipe 26.

The pipes 20 and 24' are flexible pipes to permit the movement of the pistons 15 and cylinders 10 14. When the valve 27 is turned to connect groove 31 with pipes 20 and 22, the groove 30 connects pipe 19 with pipe 26, and when the valve is turned to connect groove 31 with pipes 20 and 26, the groove 30 connects the pipe 19 15 with the pipe 22.

The valve 27 is provided with a handle 32 for manual or power operation, and both the pump 23 and valve are mounted on a transverse frame 33 which is secured at its ends to the rods 16. 20 The pump may be driven in any suitable manner and is shown as provided with a sprocket wheel 23' connected by a chain 35 with a sprocket 36 on one of the engine driven shafts 37 of the machine through any suitable clutch 37', the 25 chain being maintained at the proper tension by an idler sprocket 38 mounted on an arm 39 pivotally supported at 40 on the frame of the machine and urged outwardly by a spring 41.

With this construction when hydraulic pressure 30 fluid is introduced through the piston duct 18 into the lower end of the cylinder 14 and the fluid in back of the piston exhausted through the pipe 26, the cylinder is forced downwardly while the piston 15 tends to move upwardly. Under 35 this action of the extensible operating means the parts move from the full line position shown in Fig. 1 to a position along the axis of the dotted line there shown, and the foot 7 moves from its raised position to its dotted line lifting position.

The foot actually makes contact with the ground 40 before the levers 11 swing to the dotted line position, and as soon as contact is made, the levers 11 in swinging exert a backward pull on the links 12 and hence on the foundation 6 which is 45 then being raised through the action of the pistons 14, and as a consequence the foundation is pulled back to the full line position shown in Fig. 1. One end or the other of the foundation may be raised first depending upon the location 50 of the center of gravity of said foundation relative to said foot member. Then as the fluid is exhausted through the duct 18 and the pipe 19 from in front of the piston 14, the pressure fluid is introduced through the pipe 20 in the cylinder 55 behind the piston, and the cylinder with its parts is then moved upwardly while the piston 15 moves downwardly to the full line position shown in Fig. 1. During this movement the foot 7, lever 11, and links 12 move from their dotted 60 line position to their full line position, and the apparatus is then ready to take another step backward. As the area of the cylinder behind the piston is less than that in front, the backward stroke of the lever will take place in less time 65 than the forward stroke for the same speed of the pump 23, and in the present instance the return stroke of the extensible means takes place in half the time of the forward or lifting stroke. With this form of operating connection between 70 the foundation 6 and the foot member 7, it is only necessary to raise the foundation 6 to relieve the weight thereof so that the foundation is not raised much off the ground with the result that when it comes to rest, there is no appreciable 75 shock or jar, and as soon as the foot contacts

the ground, there is a tendency to swing the bell cranks 11, which tendency increases as the lifting force increases, and when this lifting force has increased sufficiently, the machine will walk.

With the above arrangement the foot member 5 7 is in compression under the loads imposed on it and may, therefore, be made relatively light while the bell crank levers 11 take any bending or torque strains.

The base 8 of the foundation is preferably of 10 hollow cylindrical form, and the foot member 7 has converging sides 42 curved to substantially the same curvature as the inner wall of said base 8.

To adjust the amount of lift, spaced holes 43 15 15 may be provided in the base 9 to change the position of the outer end of each link 12.

The apparatus has been arranged for the machine to walk backward. However, if the links are arranged for connection with the base 20 through holes 43' at the opposite side from the holes 43 and the foot, levers, and extensible operating connections reversed, the machine will then walk forward under the action of the relative movement between pistons and the cylinders 25 as in the first described construction.

It is to be noted that the hollow foundation 6 offers greater overall stability during the working of excavating machines, such as shovels, draglines, and cranes, than a solid base of equal 30 area or in some instances of equal outside diameter. Furthermore, since the foot member is wholly disposed within the confines of the foundation, less tail clearance for the parts on the rotating base is necessary so that the present 35 arrangement can be used for shovel type excavators and is practical in smaller sizes because of its ability to take shovel, dragline, or ditcher equipment.

While the operating means is shown as hydraulically operated, the invention is not to be limited thereto, but other forms of operating means may be used if they come within the scope of the invention as defined by the appended 40 claims.

I desire it to be understood that this invention is not to be limited to any particular form or arrangement of parts except in so far as such 45 limitations are included in the claims.

What I claim as my invention is:

1. Apparatus of the type described comprising 50 a hollow main frame determining substantially the outside dimensions of the propelling mechanism of the apparatus, a foot member working within the hollow of said main frame, each of said parts adapted to carry the other, and means connecting said frame and foot member for alternately raising said parts during translatory movement thereof in one direction.

2. Apparatus of the type described comprising 60 a hollow main foundation unit determining substantially the outside dimensions of the propelling mechanism of the apparatus, a foot member working within the hollow of said unit, each of said parts adapted to carry the other, and means 65 for connecting said foot member to said unit for raising and translatory movements of said foundation unit.

3. Apparatus of the type described comprising 70 a hollow main foundation unit determining substantially the outside dimension of the propelling mechanism of the apparatus, a foot member working within the hollow of said unit, each of said parts adapted to carry the other, a lever operatively connected to said unit and to said 75

foot member, and means for swinging said lever to raise and lower said foot member and exert a lifting and pulling action on said unit.

4. Apparatus of the type described comprising a hollow main foundation unit determining substantially the outside dimensions of the propelling mechanism of the apparatus, a foot member working within the hollow of said unit, each of said parts adapted to carry the other, a lever operatively connected to said unit and to said foot member, and extensible and contractible means connecting said lever with said unit for swinging said lever to raise and lower said foot member and exert a lifting and pulling action on said unit.

5. Apparatus of the type described comprising a hollow main foundation unit determining substantially the outside dimensions of the propelling mechanism of the apparatus and having a rotating base, a foot member working within the hollow of said unit, said unit and said foot member each adapted to carry the other, and means for connecting said foot member to said rotating base for raising and translatory movements of said foundation unit.

6. Apparatus of the type described comprising a hollow main foundation unit determining substantially the outside dimensions of the propelling mechanism of the apparatus and having a rotating base, a foot member working within the hollow of said unit, said unit and said foot member each adapted to carry the other, a lever operatively connected to said rotating base and to said foot member, and means connecting said lever at another point to said rotating base for swinging said lever to raise and lower said foot member and exert a lifting and pulling action on said unit.

7. Apparatus of the type described comprising a hollow main foundation unit determining substantially the outside dimensions of the propelling mechanism of the apparatus, a foot member working within the hollow of said unit, each of said parts adapted to carry the other, a lever operatively connected to said unit and to said foot member, and hydraulically operated means connecting said lever with said unit for swinging said lever to raise and lower said foot member and exert a lifting and pulling action on said unit.

8. Apparatus of the type described comprising a hollow main foundation unit determining substantially the outside dimensions of the propelling mechanism of the apparatus, a foot member working within the hollow of said unit, each of said parts adapted to carry the other, a lever operatively connected to said unit and to said

foot member, a hydraulic cylinder and a piston working in said cylinder, one of said last named parts being connected to said lever and the other to said unit, and means for introducing hydraulic fluid under pressure alternately on opposite sides of said piston to swing said lever to raise and lower said foot member and exert a lifting and pulling action on said unit.

9. Apparatus of the type described comprising a hollow foundation unit, a foot member working within said unit, each of said parts adapted to carry the other, a lever having one end vertically adjustably connected to said unit and an arm operatively connected to said foot member, said lever having another arm, and means connected to said last named arm to swing said lever to raise and lower said foot member and exert a lifting and pulling action on said unit.

10. Apparatus of the type described comprising a hollow foundation unit, a foot member working within said unit, each of said parts adapted to carry the other, a bell crank lever, a link operatively connecting one arm of said lever to said unit, operating means operatively connecting the other arm of said lever with said unit for swinging said lever and exerting a lifting force on said unit, both arms of said lever being connected to said foot.

11. Apparatus of the type described comprising a hollow main foundation unit, a foot member working within said unit, each of said parts adapted to carry the other, a bell crank lever, a link operatively connecting one arm of said lever to said unit, extensible and contractible operating means operatively connecting the other arm of said lever with said unit for swinging said lever and exerting a lifting force on said unit, both arms of said lever being connected to said foot.

12. Apparatus of the type described, comprising a hollow main foundation unit, a foot member working within said unit, each of said parts adapted to carry the other, a bell crank lever operatively connected to said foot member and having floating connections with said unit, and means for moving one of said floating connections to swing said lever to exert a lifting force on said unit.

13. Apparatus of the type described, comprising a frame member, a foot member coacting with said frame member, each of said parts adapted to carry the other, a bell crank lever operatively connected to said foot member and having floating connections with said frame member, and means for moving one of said floating connections to swing said lever to exert a lifting force on said frame member.
